UNITED STATES PATENT OFFICE.

GRACE C. ROGERS, OF NEW YORK, N. Y.

CORSET-COVER.

1,171,355.

Specification of Letters Patent.

Patented Feb. 8, 1916.

Application filed April 29, 1914. Serial No. 835,270.

To all whom it may concern:

Be it known that I, GRACE C. ROGERS, a citizen of the United States, residing at New York city, in the county of New York 5 and State of New York, have invented certain new and useful Improvements in Corset-Covers, of which the following is a specification.

My invention relates to new and useful 10 improvements in coverings or waists for corsets and has for its primary object to provide a simple and inexpensive article that may be readily fitted and will remain in proper position over the corset.

15 An important object of my invention is to provide a protector in the form of a waist or jacket worn over the corset in which openings are formed at the front and rear lower edges to receive the hose supporting straps 20 that are usually attached to corsets thus holding the protector against upward movement and securely in proper position.

The above and additional objects are accomplished by such means as are illustrated 25 in the accompanying drawings, described in the following specification and then more particularly pointed out as claimed.

With reference to the drawings, wherein 30 I have illustrated the preferred embodiment of my invention as it is reduced to practice, and throughout the several views of which similar reference numerals designate corresponding parts, Figure 1 is a front elevation of my improved protector, Fig. 2 is a side 35 elevation, and Fig. 3 is a fragmentary detail sectional view showing a portion of the corset and the hose supporting straps thereon inserted through one of the openings in my protector.

40 Referring to the drawings by characters of reference, the numerals 1 and 2 designate respectively the front and back sections of my improved protector which is formed in the nature of a waist. The sections 1 and 45 2 are stitched along their longitudinal edges at one side as at 3 and buttons on the other side as at 4. A preferably V-neck 5 is formed in the upper ends of the sections and arm holes 6 of the usual character provided also. 50 The device is narrowed in the center as at 7 to provide a waist to conform to the natural shape of the wearer.

The front section 1 is shorter than the one

2 and provided at its lower edge with a hem 8. A pair of openings 9 is formed in the 55 hem 8 for a purpose to be later more fully described. The openings 9 are preferably elongated and spaced considerably from each other. The lower front of the section 1 is reduced to provide a flap 10 to cover the 60 front of the wearer.

The lower part of the rear section 2 is enlarged as at 11 and shaped to conform to the back of the wearer so as to partially surround the body. The lower edge of the section 2 is provided with a hem 12 in which 65 openings 13 similar to the ones 9 are formed.

As shown in Fig. 3, A represents a portion of a corset and B one of the hose supporting straps of the usual construction attached to 70 the corset A. The straps B at the front and rear of the corset A are inserted through the openings 9 and 13 as shown in Fig. 3 and extended downwardly to be secured to the 75 hose in the usual manner.

When the hose supporting straps B are secured in the usual manner and inserted through the openings as described the protector or shield for the corset will be held securely in place and this is considered one of 80 the most essential points of my invention.

It will be readily seen with reference to the foregoing description and accompanying drawings that I have provided a simple, inexpensive and extremely useful article which 85 may be worn with great comfort as a corset protector or shield and remain in place at all times. I preferably use some flexible fabric of yielding nature in constructing 90 my protector but any suitable material may be employed.

In practice, I have found that the form of my invention, illustrated in the drawings and referred to in the above description, as the preferred embodiment, is the most efficient and practical; yet realizing that the conditions concurrent with the adoption of my device will necessarily vary, I desire to emphasize the fact that various minor changes in details of construction, proportion 95 and arrangement of parts may be resorted to, when required, without sacrificing any of the advantages of my invention, as set forth.

What is claimed is:

100 A corset cover consisting of front and rear

sections of different lengths secured together along their longitudinal edges, and each having its lower edge provided with a hem, each of the said hems having a pair of elongated openings therein, and the lower edge of the shorter section being of a lesser width than the lower edge of the longer section.

Copies of this patent may be obtained for five cents each, by addressing the "Commissioner of Patents, Washington, D. C."

In testimony whereof I affix my signature in presence of two witnesses.

GRACE C. ROGERS.
